UNITED STATES PATENT OFFICE.

JOHN T. HUME, OF CHICAGO, ILLINOIS, ASSIGNOR TO HURLEY MACHINE COMPANY, OF CHICAGO, ILLINOIS, A CORPORATION OF ILLINOIS.

AUTOMATICALLY-RELEASABLE DRIVING MEANS FOR LAUNDRY MACHINERY AND THE LIKE.

Original application filed November 2, 1922, Serial No. 598,515. Divided and this application filed April 18, 1923. Serial No. 632,842.

To all whom it may concern:

Be it known that I, JOHN T. HUME, a citizen of the United States, residing at Chicago, in the county of Cook and State of Illinois, have invented certain new and useful Improvements in Automatically-Releaseable Driving Means for Laundry Machinery and the like, of which the following is a specification.

10 For driving laundry machinery such as a clothes wringer from an electric motor, it is highly desirable to employ in the driving train an adequate means for preventing overloading of the motor, because should the 15 driven wringer be overloaded or clogged so as to result in a substantial stoppage of the motor, the motor is apt to be burned out. A general object of my invention is to provide power transmitting means automatically operable under such overload conditions to sever the operating connection between the driving element and the driven element of the train; and a further object is to provide such mechanism in a form particularly adapted for convenient embodiment in power-driven laundry machinery. Other 20 objects of my invention are to provide simple, efficient, durable and reliable mechanism susceptible of facile production and assembly for quantity manufacture and ease of maintenance and repair, and other objects will become apparent to those skilled in the art from the following description taken in conjunction with the accompanying drawings wherein I have illustrated a single embodiment of my invention incorporated in a washing machine drive. To these ends my invention consists in the construction, combinations, and arrangement of parts herein-after more fully set forth and claimed.

In the drawings Fig. 1 is an end elevation, with parts broken away, showing a washing machine and wringer actuated by driving mechanism embodying my invention; Fig. 2 is a horizontal section through the lower reach of the gear-housing, with parts in elevation; Fig. 3 is a vertical section on line 3-3 of Fig. 2; Fig. 4 is a section on line 4-4 of Fig. 2; Figs. 5 and 6 are views generally similar to Fig. 4 but showing the parts in different positions of operation; Fig. 7 is an enlarged sectional view showing the worm, worm wheel and housing arrange-

ment; and Fig. 8 is a reduced front elevation of a fragment of the machine. 55

The general construction of laundry machine herein illustrated corresponds with that shown in my co-pending application Serial No. 598,515, filed November 2, 1922, of which this application is a division. The 60 frame-sides 20 give platform-support to the electric motor or prime mover 22 from which, through my improved driving mechanism, the clothes wringer 23 is operated, as is also the movable element or cylinder 24 of the 65 washing machine. Of the wringer, it suffices here to say that the shaft 25 for one of its rolls has connecting gear structure 26 to receive power from the gear 27 on the upper end of a line shaft 33, the gearing 26 being 70 mounted in a swinging housing 28 which is rotatable to permit the wringer to be swung to different positions about a vertical axis. 75 30 indicates the motor shaft, connectable through cooperating parts to a power shaft 75 unit 31, generally horizontally arranged beneath the washing machine, and connected by appropriate gearing 32 to the upright line shaft 33 that drives the wringer gearing 26 as above stated. Preferably all of the 80 drive-parts are housed, and the housing, generally indicated at 36, is normally rigid with the frame of the machine so that it may give adequate support to various members of the drive. In general this housing comprises a horizontal tubular reach 37 for the 85 power-shaft unit, terminating in a gear box 38; a vertical reach or standard 39, the base of which is bolted to and forms a cover for the gear box 38 and the upper end of which receives the neck 28' of the gear housing 28; this vertical reach having a gear box and 90 enlargement 40 for the cylinder-reversing gearing, covered as at 41 and connected by lateral reach 42, which is end-closed as at 43, 95 with a further gear housing 44 for the cylinder drive.

If too heavy a load is imposed on the main drive shaft, as by breakage of running parts or clogging of mechanisms driven from the 100 line shaft 33, the motor 22 should not be stopped but kept free to run, and this I preferably accomplish by complete disconnection of the motor from the broken, clogged, or overloaded driven element. Therefore I provide, in the driving train and preferably in 105

the power shaft unit close to the motor, a torque-responsive positive release mechanism which, when the load on the motor shaft becomes too great, will automatically 5 operate to disconnect the motor completely from its normal mechanical connection with the line shaft 33 and preferably will maintain such disconnection until the device is reset in closed or connected relation. Such 10 automatic release mechanism I provide in the form generally indicated at 45, Fig. 2.

The motor shaft 30 finds effective continuation in clutch-shaft 50, and, through the clutch of the release mechanism 45 it 15 may drive the gear shaft 51. Preferably a universal joint 52 of suitable construction connects shafts 30 and 50 outside of the lower reach 37 of the housing, screw-cap 53 closing the end orifice of the housing 20 through which the housing-contained shafting may be withdrawn. A thrust-collar 54 detachably secured in the housing gives bearing to the shaft 50 and positions one disc-head of a positive clutch 55, the tooth 25 or teeth 55^a of which may coact with the tooth or teeth 55^b of a similar disc-head on gear shaft 51. The coacting faces of the clutch teeth are preferably slightly beveled so that the driven clutch member may easily 30 escape from the driving clutch member when shaft 51 is moved axially forward as shown in Figs. 5 and 6. Gear shaft 51 is so mounted as to permit the sliding disengagement of the clutched surfaces. At its 35 rear end it finds bearing in a sliding sleeve 56, and at its forward end it is slidably supported in a bracket 57 cast in the housing. Between these bearings the shaft has a worm 58 to drive (counterclockwise in 40 Fig. 2) the line-shaft worm gear 59, as one specifically desirable provision of a gear structure 32.

As a desirable means for imposing 45 definite resistance to the torque-responsive opening of the clutch 55, and also for giving a snap-action on the opening and a positive maintenance of the clutch in opened condition until it is manually reset, I make the following provision: Rack 61 on the 50 shiftable sleeve 56 engages a pinion 62 which is vertically disposed in bearings in the housing 37, the pinion-arbor carrying a handle 63 (Fig. 3) conveniently located for manual operation. At its lower end the 55 pinion-arbor carries a lever 64, horizontally vibratable and connected to a toggle-link 65, the opposite end of which is connected to a spring-block 66 that slides in a chambered bearing-stud 67 and is constantly 60 pressed outward by a spring 68, the tension of which is adjustable by the movement of a bearing screw 69.

The action of this torque-responsive release means is fully shown in Figs. 2, 5 and 6. Normally, the clutch 55 stands

fully engaged, and normally the resistance of toggle spring 68 working through the toggle-levers in the "closed" position shown in Fig. 2 suffices to hold the clutch fully closed. When the resistance, or load, opposing movement of worm gear 59 in its counterclockwise direction of rotation (Fig. 2) becomes sufficiently high, however, the worm 58, carrying the sleeve 56, advances 70 axially rotating the pinion 62 of the releasing mechanism by reason of the movement of rack 61 on the stated sleeve 56. Of course the rotation of pinion 62 must be effected against the increasing pressure of spring 68 until the station shown in Fig. 5 75 is reached, where the toggle 64-65 passes dead center. As soon as dead center is passed, the action of spring 68 becomes effective to augment the clutch-opening tendency, and the spring throws the toggle levers to the position shown in Fig. 6, snapping the clutch fully open and holding it there. Thus, with a very short axial movement and a very compact construction of the parts, I am able to effect both a very 80 positive clutch engagement for normal operation and a very positive release and maintenance of the clutch in open position under strain-conditions that are accurately settable by suitable adjustment of the tension screw 69 for the spring 68.

Of course it is desirable that the large worm gear 59 be accurately positioned, and in the gear case 38 a stepped bearing 71 may be provided, carried on ribs 72 affording a centralizing bearing-hub 73 that fits into a recess in the worm wheel, this hub also forming a bottom bearing for the upright line shaft 33 which makes spline-engagement with the gear 59 so that the shaft may be withdrawn vertically from the stepped bearing and the gear. Thus it will be seen that all of the parts referred to are readily removable from the housing structure. 100

It will be understood by those skilled in the art that while I have herein described in detail a particular embodiment of my invention for purposes of full disclosure thereof, and some of the detail features of which I may claim for their specific advantages, still in the broader aspects of my invention many changes in details of construction and arrangement of parts may be made without departure from the spirit of 105 the invention and within the scope of the appended claims. 110

I claim:

1. The combination of a prime mover, a load-carrying structure, a worm gear constantly connected for driving the load-carrying structure, an axially-shiftable clutch-shaft having a worm engaging said worm gear and having a toothed clutch member, a shaft connected with the prime mover and 115 120 125 130

having a toothed clutch member positively engageable with the first said clutch member, an axially slidible sleeve in which said clutch shaft is mounted, said sleeve being

5 provided with rack-teeth, a pinion meshing with said rack, and a spring-pressed toggle mechanism acting on said pinion, substantially as described.

2. The combination of a prime mover having a shaft, a load-carrying structure to be driven, a clutch-shaft aligning with the motor shaft, positive clutch members interposed between said two shafts and having beveled coacting faces, one of said clutch members being axially movable away from the other under sufficient torque, a rack axially movable with said clutch member, a pinion operatable by said rack, a lever on said pinion, a spring-pressed toggle link normally holding said lever in one limit of movement and arranged to snap over past dead-center

to throw said lever positively to another limit of movement and thereby positively separate the axially movable clutch member from its fellow.

25

3. The combination of a prime mover having a shaft, a load-carrying structure to be driven, a clutch-shaft aligning with the motor shaft and axially movable with respect thereto, confronting positive clutch members on the ends of said respective shafts having beveled coacting faces, and means normally acting to resist movement of the relatively movable shaft away from the motor shaft comprising a spring-pressed toggle mechanism and operative connections between said toggle mechanism and the axially movable shaft, said toggle mechanism having its levers arranged in approximate parallelism to the movable shaft.
